UNITED STATES PATENT OFFICE.

GUILLERMO E. FREUDENTHEIL, OF HAMBURG, GERMANY.

PIANO-FRAME.

SPECIFICATION forming part of Letters Patent No. 239,949, dated April 12, 1881.

Application filed June 11, 1880. (No model.) Patented in Germany February 13, 1880.

To all whom it may concern:

Be it known that I, GUILLERMO EUGENIO FREUDENTHEIL, of Hamburg, in the German Empire, have invented Improvements in Iron 5 Frames for Piano-Fortes, (for which I have obtained German patent of fifteen years, from February 13, 1880, No. 8,840;) and I do hereby declare that the following is a full and exact 10 description thereof, reference being made to the accompanying drawings.

Figure 1 is a top view of my improved piano-forte frame. Fig. 2 is a cross-section on enlarged scale thereof. Fig. 3 is a partial top view of part thereof. Fig. 4 is a side and a 15 sectional view of the wooden socket-piece for the turning-post; Fig. 5, a top and sectional view of a modification of the adjustable rest.

These improvements comprise a combination of the following essential elements: the 20 iron frame cast in one piece with the sound-post and double shoes, fastening-plate, and cross-stays. The pins are sunk into wooden sockets inserted into the iron sound-post.

The frame A is cast in one piece with the 25 sound-post a, the fastening-plate f, the double shoe d d, and the cross-stays g. This frame is preserved from any influence of the atmospherical variations, the influence of which is so troublesome for wooden frames, even when 30 they are garnished with iron sheets.

The pins i are sunk—that is to say, they are fastened on the iron sound-stock a—in the following manner, Figs. 2 and 4 of the drawings: After the holes b are bored into the sound- 35 post a they are fitted with sockets c, of hard cross-grained wood. These round or oval sockets are to be puttied or otherwise secured in place, after which they are perforated with holes the diameter of which corresponds to 40 the size of the pins i, the rotation of which will be more or less easy, according as the holes are larger or smaller. This system renders it impossible for the pins to get rusty.

The parallel double shoes d, Figs. 1, 2, and 45 3, cast in one piece with the sound-post, serve

for crossing the strings. Between these shoes lies the metal bar e, by which the strings are held down, the tension being regulated by means of screws h. By this means the strings are stretched in an equal way by a middle 50 pressure, losing at the same time the force which they were exercising under the old system, in consequence of their oblique direction. My cramp, consisting of the parts d e d, is easy to adjust, and the danger of the warping 55 of the wood is avoided. The modification of this cramp shown in Fig. 5 illustrates a further rest, j, beneath the bar e, between the shoes d.

The tone of a piano-forte provided with my 60 improvements is excellent and durable. At the same time the sonorousness, the force, and the sweetness of the sounds are favored in a considerable manner by the massive iron frame. Even the weight is less in my construction 65 than in instruments having wooden sound-posts, as I am not compelled to make use of cross-stays.

I am aware that the above-described elements, which I claim to have combined, are 70 in themselves old, and I do not claim them nor any of them separately, but only their combination, which produces results not attainable by the separate use of said elements.

I claim—

In piano-fortes, the iron frame A, cast in one piece with the sound-post a, the fastening-plate f, the cross-stays g, and double shoes d, in combination with the wooden socket c, pins or posts i, and with the adjustable bar e and 80 screws h, substantially as herein shown and described.

In testimony that I claim the foregoing I have hereunto set my hand this 20th day of October, 1879.

G. E. FREUDENTHEIL.
